US00D429384S

United States Patent [19]

Crupi et al.

[11] **Patent Number:** Des. 429,384[45] **Date of Patent:** ** Aug. 8, 2000[54] **PROTECTIVE BODY SUIT**

[75] Inventors: **Vince Crupi**, Ottawa; **Donald Alexander Gunn**, Orleans; **Shaik Kalaam**, Nepean; **Richard J. L'Abbé**, Ottawa; **Aristidis Makris**, Nepean; **Ron Purvis**, Orleans, all of Canada

[73] Assignee: **Med. Eng Systems Inc.**, Ottawa, Canada

[**] Term: **14 Years**

[21] Appl. No.: **29/078,413**

[22] Filed: **Oct. 15, 1997**

[51] LOC (7) Cl. **29-02**

[52] U.S. Cl. **D29/100**

[58] Field of Search D29/100, 101; 2/455, 456, 457, 458, 2.11, 2.14, 2.15, 466
